(57) **CLAIM**

I claim the ornamental design for a surveillance camera, as shown and described.

DESCRIPTION

FIG. 1 is a front perspective view of an embodiment of a surveillance camera, showing my new design;

FIG. 2 is front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a back perspective view thereof.

The dashed lines shown in the drawings illustrate portions of a surveillance camera that form no part of the claimed design.
